UNITED STATES PATENT OFFICE.

EDWARD FALES, OF WINTHROP, MASSACHUSETTS.

STOVE.

SPECIFICATION forming part of Letters Patent No. 617,727, dated January 17, 1899.

Application filed December 7, 1897. Serial No. 661,052. (No model.)

To all whom it may concern:

Be it known that I, EDWARD FALES, a citizen of the United States, residing at Winthrop, in the county of Suffolk and State of Massachusetts, have invented certain new and useful improvements in Stoves, of which the following is a specification.

My invention relates to heating apparatus, and it has reference particularly to such heating apparatus in which coal or analogous substances are burned as the fuel.

The principal object of my invention is to provide a stove of a construction that will improve and tend to materially perfect the combustion of the fuel that is to be burned in said stove and that will afford a maximum amount of heat for a comparatively small amount of radiating-surface.

My invention is fully illustrated in the accompanying drawings, in which—

Figure 1 is a vertical sectional view of the invention. Fig. 2 is a horizontal sectional view of the stove-body, taken just above the fuel-support. Fig. 3 is a vertical sectional view of a portion of a stove-body provided with a modification of my invention, and Fig. 4 is a perspective view of an element which I term a "retarder-plate."

Like numerals of reference represent corresponding parts on the drawings.

In said drawings, 1 represents the body of the stove, which is made of sheet metal and which is preferably of cylindrical form, though other forms may be adopted. The body of the stove is supported upon a base 2, provided with suitable legs 3 and an upwardly-projecting flange or collar 4, to which the lower end of said stove-body is secured by means of rivets or bolts, &c. A suitable top plate 5 surmounts the body portion of the stove and is provided with a downwardly-extending flange 6, to which the top end of the stove is bolted or otherwise secured.

At the front of the stove and conforming to the shape thereof is secured in any desirable manner a frame 7, to which are hinged three doors 8 9 10, which are the fuel-supply, poker, and ash-pit doors, respectively, and which register with openings that are provided in the wall of the body of the stove. Bolted or riveted on the inside of the stove opposite the poker-door are angular lugs 13, supporting

on their top edges an annulus 14, forming an overhanging ledge, which annulus may loosely rest thereon. Said annulus is adapted to serve as a support for fire-brick 15, arranged entirely about the inside of the stove and extending upwardly into proximity to the bottom of the fuel-supply aperture, as shown in the drawings. For the fire-brick an annular water-box 60 may be substituted, if desired, as in Fig. 3 at 15^a. An imperforate plate is seated upon lugs 13, the outer edge of said plate being situated in proximity to but not in contact with the stove-wall. The annulus 14 therefore projects considerably over the edge of the plate 16. To insure the seating of this disk in such a position that the surrounding space will be approximately uniform, several radially-projecting and integral lugs may be provided, 70 and such lugs appear in the drawings, where they are indicated by the numeral 17. The upper surface of said disk 16, which, as is obvious, is intended to serve as the fuel-support, should be arranged approximately in 75 the plane of the bottom of the poker-door in order that the fuel and the refuse thereof supported by said disk may be readily accessible by means of a poker inserted at the poker-door. Above the fuel-supply inlet is 80 arranged another disk 19, which constitutes what I have termed a "retarder-plate," and which is so secured in position by means of a series of radial projections 19^a, that are bent downwardly and fixed to the wall of the 85 stove, as to leave an annular space between its edge and said wall. The fuel-support 16 and the retarder-plate 19 thus divide the space inclosed by the stove-body into three chambers, which are an ash-pit, a combustion-chamber, and a heat-radiating chamber. I have found that the combustion-chamber should preferably be the smaller of the three chambers, and hence the fuel-support and the retarder-plate are shown as arranged close 90 enough together to this end.

From the top of the heat-radiating chamber leads a suitable discharge for the products of combustion.

The annular space which surrounds the retarder-plate is so proportioned with reference to the combustion-chamber that while permitting the incombustible and highly-heated products of combustion to escape the outflow

of the still unconsumed gases is at least retarded.

In so far as the use of an imperforate form of grate is concerned the operation of this stove is the same as the operation of the furnaces described in Letters Patent Nos. 584,815 and 584,816, issued to me June 22, 1897. In the case in hand, however, since it is practically impossible, owing to the construction 10 of the stove, to augment the proper union of the air and gases by directing the former over a heated surface from which bodies of the latter are rising it becomes necessary to give the air that has already been in continuity to the fuel a redirection toward the same, so that it may thus become thoroughly mingled with the rising gases. The function 15 of the retarder-plate will therefore be now recognized. This plate is arranged with a view not only to redirecting the rising bodies 20 of air at such a distance from the grate that they will accomplish the desired object, but also to reducing the size of the combustion-chamber, so that the successful diffusion and 25 commingling of the air and gases will take place in a comparatively small space. By confining the operation which takes place 30 within the large combustion-chamber of either of the furnaces disclosed in my patents referred to above to the relatively small 35 space contained within a cylindrical stove of the type illustrated in my drawings I secure a very considerable increase of heating capacity from a stove of this class.

If the retarder-plate were not employed, the height of the combustion-chamber would have to be increased far beyond the desirable limit in order to secure the necessary diffusion and commingling of the various gaseous elements; 40 but by using said retarder-plate I cause the said gaseous elements to reverberate within the combustion-chamber, thus producing innumerable eddies and counter-currents and a consequent and thorough admixture of all 45 the bodies of gas which, if not turned back upon their courses, would be likely to pass away from the apparatus without being chemically united with other bodies of gas, for which, under a sufficiently high degree of heat, 50 they have great chemical affinity.

I am aware that it is old to provide combustion-chambers with deflectors, so that the products of combustion may be detained within said chambers until a large portion of 55 the heat which they hold has been absorbed by the apparatus, and thus made effective for heating purposes, and such deflectors I do not claim or regard as within the scope of my invention. These deflectors have heretofore 60 always been used with a grate that is provided throughout the whole or a portion of its area with air-inlet openings of one shape or another, through which the air passes to the solid pieces of fuel which the grate sustains. 65 According to the principle of my invention it is imperative that the fuel-supporting element should be of such a character as to prac-

tically exclude air from the main body of the solid fuel. The admission of air is confined to the marginal edges of the body of said fuel, 70 so that while certain portions thereof are being rapidly consumed other portions are suffering destructive distillation only, and thus supplying the combustion-chamber with considerable bodies of inflammable gases. 75

If an ordinary grate were employed in the apparatus which I have illustrated, a much larger volume of combustible gases would be generated and could not be perfectly consumed within the combustion-chamber of the 80 apparatus; but by utilizing the imperforate fuel-support instead of such a grate the volumes of combustible gases and of air are so proportioned that practically all of said gases are perfectly consumed below the level of the 85 retarder-plate.

As far as I understand the workings of my apparatus it is not absolutely necessary that the air should be admitted at the margin of the fuel-support. If the fuel-support has relatively large imperforate areas and the flow 90 is confined to the limited areas of the solid fuel, the objects at which I aim will be attained. My invention is therefore so broad as to include any kind of combustion apparatus in which the combustion-chamber approximates equal vertical and lateral dimensions and which includes an imperforate fuel-support and means for admitting a limited supply of air to the space above said fuel-support, as well as a retarder-plate that is capable of causing a reverberatory action to the currents of air and combustible gases without interfering with the necessary escape 95 of the products of combustion to an abnormal extent. 100

I do not deem it necessary that an apparatus falling within the principles of my invention should operate in such a way as to confine the zone of combustion to the space below the retarder-plate, because in any apparatus whatever it is difficult to draw a sharp line of demarcation between the combustion-chamber and the outlet-passage of the apparatus; and, so if flame is observed in the 115 space above the retarder-plate it should not be concluded that the operations which I regard as essential are not being performed within the space below said retarder-plate. 120

The preferred form of the apparatus is that shown in the drawings of this application, wherein the air is admitted only at the margin of a circular fuel-support. The effect of this construction is to surround a body of combustible gases with a substantially cylindrical and thin wall of air, through which the body of gas will have to pass before it or any portion thereof can escape into the exit-flue. It is practically impossible for any particular body of gas to pass from the point of 130 generation out of the apparatus without being diffused into some portion of the cylindrical wall of air or some detached body of air. All the air which enters the combustion-

chamber is heated by direct impact upon the igneous fuel lying at the margin of the fuel-support, thus preventing the chilling influences which frequently prevent the union of elements which, if sufficiently heated, have a great chemical affinity for each other. The body of fuel thus lying at the margin of the fuel-support does not utilize all of the air that is brought in contact therewith. Portions of the inflowing air do support combustion in this marginal body of fuel; but other portions are merely heated upon contact therewith and, as indicated, flow into the combustion-chamber to afterward mingle with the gases generated by the process of destructive distillation.

Although the annulus 14 may be considered as a special and independent means for imparting an inward movement to the incoming air after the same in entering the combustion-chamber has passed through the inlet that surrounds the fuel-support, it is obvious that the said inlet may be considered as extending as far as the inner edge of the annulus and as therefore being such an inlet or duct as will of itself impart the desired inward movement to the incoming air without any other means for accomplishing this.

Having thus fully described my invention, what I claim, and desire to secure by Letters Patent of the United States, is—

1. In a heating apparatus, means for introducing the air for combustion at or near the edges of the body of fuel and on all sides thereof, means for causing the air to move inwardly over the body of the fuel and means for retarding and causing the gases to return upon themselves, substantially as described.

2. A cylindrical heating - stove having a circular imperforate fuel-support arranged

therein and spaced from the wall thereof to form an annular air-passage, means for directing the air inwardly from said air-passage, and a retarder-plate situated above said fuel-support, substantially as described.

45

3. A cylindrical heating - stove having a circular imperforate fuel-support therein and spaced from the wall thereof to form an annular air-passage, a ledge situated above said passage and projecting over the edge of said fuel-support, and a retarder-plate situated above said fuel-support, substantially as described.

50

4. A cylindrical heating - stove having a circular imperforate fuel-support arranged therein and spaced from the wall thereof to form an annular air-passage, an annulus situated above said support, projecting over the edge thereof and providing a ledge, a water-box arranged on said ledge, and a retarder-plate situated above said fuel-support and above the water-box, substantially as described.

55

5. In a combustion apparatus, the combination with the combustion-chamber, of a substantially imperforate fuel-support and a retarder-plate arranged in said chamber, the latter being above the former and spaced from the walls of said chamber, and an air duct or ducts surrounding said fuel-support and adapted to direct the air inwardly toward the center of said combustion-chamber, substantially as described.

60

In testimony whereof I affix my signature in presence of two witnesses.

EDWARD FALES.
